(57) **CLAIM**

The ornamental design for a tool box as shown and described.

DESCRIPTION

FIG. 1 is a front elevational view of a tool box showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a side perspective view thereof; and

FIG. 8 is a top perspective view thereof;

FIG. 9 is a bottom perspective view thereof; and,

FIG. 10 is a side perspective view thereof showing a state of use of the tool box together with a base and a top cover. The broken lines in FIG. 5 illustrate portions of the tool box that do not form part of the claimed design.

The broken lines in FIG. 10 illustrate environmental features that do not form part of the claimed design.
